UNITED STATES PATENT OFFICE.

CHARLES FISHER, OF CHICAGO, ILLINOIS, ASSIGNOR TO THE AUTOMATIC RECORDING
SAFE COMPANY, OF CHICAGO, ILLINOIS, A CORPORATION OF ILLINOIS.

SAVINGS BANK.

Application filed June 18, 1921. Serial No. 478,625.

To whom it all may concern:

Be it known that I, CHARLES FISHER, a citizen of the United States, residing at Chicago, in the county of Cook and State of Illinois, have invented a new and useful Improvement in Savings Banks, of which the following is a specification.

This invention relates particularly to dime savings banks; and the primary object 10 is to provide an exceedingly simple savings bank of this character which can be made very inexpensively and which can readily be embodied in a pleasing design.

The invention is illustrated in its preferred embodiment in the accompanying drawing, in which—

Fig. 1 represents a perspective view of the improved savings bank; Fig. 2, an inner perspective view of one of the sections thereof; Fig. 3, an inner perspective view of the other section thereof; Fig. 4, a broken perspective view showing a portion of the side wall of the section shown in Fig. 3 and illustrating the relation thereto of a locking member employed; Fig. 5, a broken sectional view of the wall shown in Fig. 4, this view showing a key in position; Fig. 6, a broken vertical sectional view showing the sections of the casing locked together; Fig. 20 7, a broken horizontal section taken as indicated at line 7 of Fig. 6; Fig. 8, a plan view of a slot-guard housing member, showing the wire slot-guards in position; and Fig. 9, a broken vertical sectional view 25 taken as indicated at line 9 of Fig. 8, but showing the housing member connected with the top wall of the casing-section.

In the form of the invention illustrated, two casing sections A and B are employed, 40 each of these sections having the outline of a keystone. These sections are adapted to fit together telescopically, the section A being slightly larger than the section B.

The section A comprises a main vertical wall 1 which forms the front wall of the casing; a bottom flange 2; a top flange 3; and side flanges 4, 4. The top flange 3 is preferably curved or arched. The bottom flange 2 is shorter than the top flange, and 50 the side flanges 4 are convergent from the upper end to the lower end of the casing section. The main wall 1 preferably bears an embossment 5 which has the conventional

form of a keystone. This may be provided by striking the metal outwardly, as illustrated.

The section B is of corresponding shape, but slightly smaller. This section has the main vertical wall 1^a; the bottom flange 2^a; the top flange 3^a; and the side flanges 4^a.

The casing sections are equipped on the inner surface of their side walls with locking members which are adapted to automatically engage and lock the sections together, when the sections are pressed together in telescopic relation.

The casing section A has secured to the inner surface of its main wall a U-shape rigid sheet-metal member 6, the web portion 6^a of which is secured to the main wall by 70 rivets 7. The upper flange or arm 6^b of the member 6 serves as a guard which is disposed between the coin-admission means and the locking members. The flange 6^b is preferably made crowning or arched, as 75 shown. The lower flange or arm 6^c of the member 6 has its extremity provided with a downwardly turned locking lug 6^d. The flange 6^c is also recessed or notched, as indicated at 6^e to provide a passage for the 80 stem portion of the spring locking member with which the other casing section is equipped.

The main wall of the casing section B has secured to its inner surface a vertically disposed spring-arm 8 which has at its upper portion a laterally turned catch or locking lug 8^a which is provided with a beveled edge 8^b. The member 8 also has at its rear edge an upwardly projecting stem or key-engaging member 8^c. The locking lug 8^a and the key-engaging member 8^c are provided by splitting the metal of the member 8 and bending a portion of it laterally to provide the locking lug, while the remaining portion is allowed to extend vertically to afford a portion adapted to be engaged by the key. The spring-arm 8 is shown as comprising a piece of spring metal, preferably sheet metal, having at its lower end portion a 100 laterally extending flange 8^d which is secured to the main wall of the casing section by rivets 9. The rear edge 8^e of the locking member 8 is beveled, as indicated in Fig. 7, and engages the locking lug 6^d 105 of the other casing section, the lug 6^d being

twisted slightly from a plane parallel with the plane of the wall 1 so as to afford a beveled surface which corresponds approximately with the beveled surface 8^e. The purpose of the bevels is to cause the casing sections to be drawn into the closest possible telescopic relation through the force of the spring-arm 8 when the locking members engage each other.

10 The main wall 1^a of the casing-section B is provided with a key-receiving perforation 10 and concentrically with an interior embossment 10^a formed by striking the metal inwardly. The metal is further provided with a slot 10^b to enable the bit of the key to enter. At one side of the embossment 10^a is a fillet or raised portion of metal 11 which presents a shoulder or stop 11^a at the upper side of the embossment 10^a and which presents a shoulder or stop 11^b at the lower side of the embossment 10^a. The shoulder 11^a is immediately adjacent the key-bit slot 10^b, and the shoulder 11^b is slightly removed from a vertical plane 25 which passes thru the key-bit slot. The purpose of the shoulder 11^a is to prevent the key from being rotated in the wrong direction; and the purpose of the shoulder 11^b is to afford a stop for the key-engaging portion 8^e of the member 8 when the locking member is retracted by the key. In other words, the stop 11^b will permit the necessary retraction of the locking lug 8^a, but will prevent the key from being turned 30 wholly around in its socket. The expedient thus serves to prevent possible disarrangement of the locking mechanism, and also serves to insure the rotation of the key in the right direction in effecting release.

40 The key is designated 12. It is provided with a knob or handle 12^a, with a circular flange 12^b, and with a key-bit 12^c. The embossment 10^a is preferably formed by striking the metal of the wall 1^a inwardly, as will be understood from Fig. 5. The circular flange 12^b is adapted to rotate in the recess thus formed in the wall 1^a, while the inner end portion 12^c extends through the perforation 10 and carries the key-bit 12^c. 45 The key-bit projects laterally from the barrel portion 12^d and has a projection 12^e which is shaped to conform to the embossment 10^a, about which the projection is adapted to rotate in the unlocking operation.

50 The projection 12^e is adapted to engage the projection 8^e of the spring-arm 8. It will be seen, therefore, that the formation of the key is such that the portion which engages the member 8^e is shielded by the embossment 55 10^a.

By forming a counter-sunk opening for the key in the wall 1^a and providing the key with the flange 12^b and with a bit which will conform to the embossment 10^a, the use 60 of a separate key-barrel is rendered unnecessary,

inasmuch as the key will have a good bearing in the wall 1^a.

The top flange 3 of the casing section A is provided with a coin-slot 13. The top wall 3^a of the casing section B is provided with a corresponding coin-slot 13^a. The inner surface of the flange 3^a is equipped with a slot-guard housing 14 which is provided with a coin-slot 13^b which registers with the coin-slot 13^a. The member 14 may be 75 formed of thin sheet-metal, and it has the metal struck downwardly as indicated at 14^a to provide a shallow chamber for wire slot-guards 15 and 16. These wire members are simply laid in the shallow chamber 80 and the member 14 is then secured to the top wall 3^a. The parts are secured together by means of clenching lugs 17 which are struck inwardly from the flange 3^a, which extend through perforations 18 in the end 85 portions of the member 14, and which are clenched beneath the member 14, as will be understood from Fig. 9.

Each of the wire springs 15 and 16 is of general U-form, but one arm of each spring 90 is bent and extended obliquely across the coin-slot. Thus, the spring 15 has a straight arm 15^a, a loop 15^b, and an arm 15^c which is bent to extend obliquely across the coin-slot, the end portion of the tongue 95 thus afforded being curved, as indicated at 15^d. The arm 15^a lies along one lateral wall of the recess 14^a. The spring 16 is formed like the spring 15 but is reversed in position. The parts are designated by the numeral 16, with indices corresponding with the indices already used with respect to the spring 15. When the springs are placed in position in the chamber 14^a in the manner shown in Fig. 8, they bear against each other, so as to mutually hold each other in position. Obviously, when a coin is inserted between the spring tongues, the tongues will yield to permit the passage of 100 the coin.

When the casing sections are brought together telescopically, the locking lug 8^a of the spring arm 8 will automatically engage the locking lug 6^a, thus locking the sections together. The member 6 forms a housing 115 within which the inner end of the key may turn to effect release of the locking lug 8^a from the locking lug 6^a. The flange 6^b of the member 6 forms a shield which is preferably curved, so that when coins are inserted thru the coin-slot, they will roll off the shield and fall into the chambers on opposite sides of the vertical spring arm 8. The spaces flanking the spring arm 8 are somewhat greater than the diameters of the 120 coins, so that the necessary freedom of movement of the spring-arm is allowed.

When the spaces flanking the spring-arm become filled, the coins will accumulate in the upper portion of the casing. However, 130

the member 6 will always preserve a chamber within which the inner end of the key may rotate to effect the unlocking operation.

The casing sections may be formed of suitable sheet-metal, by a stamping or drawing process. Thin sheet aluminum, or thin sheet brass may be used advantageously. The improved savings bank is exceedingly simple, may be manufactured at very moderate cost, and may be made very light. In a desirable embodiment of the device, it may be easily made of a size to be slipped into a vest pocket.

When it is desired to separate the sections, the key may be inserted and rotated to release the lock and the key may then be used as a handle to withdraw the inner section from the outer section, while the flanges of the outer section are grasped between the thumb and fingers.

The foregoing detailed description has been given for clearness of understanding only and no unnecessary limitations should be understood therefrom, but the appended claims should be construed as broadly as permissible in view of the prior art.

What I regard as new, and desire to secure by Letters Patent, is—

1. A savings bank comprising a pair of open-sided casing sections, the outer section having a lateral peripheral flange adapted to receive the inner section, a locking member secured to the inner surface of the main wall of one of the sections, a co-acting movable locking member secured to the inner surface of the main wall of the other casing section, said last mentioned section having a key-receiving perforation through its main wall through which a key may be operated to actuate said movable locking member, and coin-admission means extending thru the peripheral flange of the outer casing section.

2. A savings bank comprising a pair of open-sided telescopic casing sections having lateral peripheral flanges which telescope with each other, a rigid locking member secured to the inner surface of the main wall of one of the casing sections near the center thereof, a movable locking member disposed adjacent the inner surface of the main wall of the other casing section and adapted to engage said first-named locking member, and a key, extending thru the main wall of the last-mentioned casing section and adapted to actuate the locking member thereof.

3. A savings bank comprising a pair of open-sided telescopic casing sections having lateral peripheral flanges which telescope with each other, a rigid locking member secured to the inner surface of the main wall of one of the casing sections near the center thereof, a movable locking member disposed adjacent the inner surface of the main wall

of the other casing section and adapted to engage said first-named locking member, and a key extending thru the main wall of the last-mentioned locking section and adapted to actuate the locking member thereof, said key being adapted to interlockingly engage the casing section and to afford a handle for withdrawing the casing section.

4. A savings bank comprising a pair of open-sided telescopic casing sections, one of said sections having the inner surface of its main wall equipped with a substantially rigid locking member, and the other casing section being equipped interiorly with a coacting spring-actuated locking member, and a key extending thru the main wall of said last-mentioned casing section near the center thereof, said key being adapted to serve as a handle in the operation of separating the casing sections.

5. A savings bank comprising a pair of open-sided telescopic casing sections provided with lateral peripheral flanges, the top flanges being provided with registering coin-admission slots, a rigid locking member carried by the inner surface of the main wall of one of said casing sections, and a shield disposed some distance above said locking member and some distance beneath the coin-slot, a spring actuated locking member disposed adjacent the inner surface of the main wall of the other casing section, and a key working thru said last-mentioned wall and adapted to retract the spring-actuated locking member.

6. A saving bank comprising an outer casing-section having a main vertical wall and a peripheral flange, an inner casing section having a main vertical wall and a peripheral flange, a rigid member secured to the inner surface of the main wall of the outer casing section and having a portion which serves as a shield and a portion which serves as a locking lug, a vertical spring arm mounted in the inner casing section and having a locking lug adapted to engage said first-named locking lug, the main vertical wall of the inner casing section having a key-opening through which a key may operate and adapted to retract the locking lug carried by said spring-arm.

7. A savings bank comprising an outer casing section provided with a main vertical wall and a peripheral flange, said peripheral flange being equipped with a coin-slot, a shield within said section and disposed some distance below said coin slot, a locking lug carried by said section and disposed some distance below said shield, an inner casing section provided with a main vertical wall and a peripheral flange, said flange having a registering coin-slot and being equipped with slot-guards, a centrally disposed spring-arm rising from the lower portion of the

- inner casing section and provided with a locking lug adapted to engage said first-named locking lug, and a key working thru the main wall of the inner casing section, 5 the inner end of said key being adapted to turn within the space between said shield and first-mentioned locking lug.
8. A savings bank comprising an outer casing section provided with a main vertical wall and with a peripheral flange equipped with a coin-slot, a U-shape member secured to the inner surface of said main wall, the upper portion of said U-shape member serving as a shield and the lower portion thereof 10 carrying a locking lug, an inner casing section provided with a main vertical wall and a peripheral flange equipped with a coin-slot and a slot-guard, a spring-arm secured to the lower portion of the inner casing section and extending upwardly therefrom, 15 said spring-arm being equipped with a laterally extending locking lug provided with a beveled edge and being equipped also with a key-engaging lug extending above 20 said locking lug, and a key journaled in the main wall of said inner casing section and provided with a bit adapted to engage said last-mentioned lug.
9. A savings bank comprising a pair of telescopic casing sections, one of said sections being equipped interiorly with a substantially rigid locking lug spaced some distance from the main vertical wall and the other section being equipped with a spring- 25 arm provided with a locking member adapted to engage said first-named locking lug, the main wall of said last-named section being provided with a key-opening, an inwardly struck embossment concentric 30 with said key-opening, and a key journaled in said embossment and provided at its inner end with a key-bit having a projection working over said embossment.
10. A savings bank comprising a casing section having a main wall and a peripheral flange, a locking member carried by said main wall, a second casing section having a main wall and a peripheral flange, a spring-arm carried by said second-named section 45 and equipped with a coacting locking lug, said last-mentioned wall being provided with a key-opening and with an inwardly struck embossment, a key journaled in said embossment and having a bit with a projection overhanging and conforming to said embossment, and stops on the inner surface of the main wall of said second-named section serving to limit the rotation of the key.
11. A savings bank comprising an outer casing section having a main vertical wall and a peripheral flange, said main wall being equipped on its inner surface with a locking lug spaced with relation to the main wall, an inner casing section having a main vertical wall and a peripheral flange, the 50 main wall of said inner section having an inwardly struck embossment with a key-opening therethru, a stop immediately adjacent one side of the slot of the key-opening, and a key journaled in said embossment 70 and having a bit provided with a projection adapted to work over the embossment and engage said stop.
12. A savings bank comprising an outer casing section having a main vertical wall and a peripheral flange, a locking lug mounted on the inner surface of the main wall and spaced with relation thereto, an inner casing section having a main vertical wall and a peripheral flange, a spring-arm mounted in the lower portion of the inner section and extending upwardly therefrom, said arm having a laterally turned locking lug at its upper portion and having a key-engaging lug extending above said locking lug, an inwardly struck embossment in the main wall of said inner casing section having a key-opening therethru, a stop at one side of the slot of the key-opening at the upper side of said embossment, a stop at the lower side of said embossment adapted to be engaged by the key-engaging portion of said spring-arm, and a key journaled in said embossment and having a bit provided with a projection working over said embossment. 95
13. In a savings bank, a casing section comprising a main vertical wall and a peripheral flange, a spring-arm secured to the lower portion of said casing section and extending upwardly therefrom and provided at its upper end with a laterally turned locking lug and with a key-engaging lug extending above said locking lug, and a key-opening in said main wall above said key-engaging lug. 100
14. In a savings bank, a casing section comprising a main vertical wall and a peripheral flange, a spring-arm secured to the lower portion of said casing section and extending upwardly therefrom and provided at its upper end with a laterally turned locking lug and with a key-engaging lug extending above said locking lug, and an inwardly struck embossment in the main wall above said key-engaging lug, said main wall being provided with a key-opening extending thru said embossment. 110
15. In a savings bank, a casing section comprising a main vertical wall and a peripheral flange provided with a coin-slot, a slot-guard housing secured to said peripheral flange and provided with a registering coin-slot, and a pair of wire slot-guards lying nested in said housing and having tongues extending obliquely across the coin-slot. 120
16. A savings bank comprising an outer casing section having a main vertical wall, a bottom flange, side flanges and a top flange, 130

said top flange being provided with a coin-slot, a U-shape member secured to the inner surface of the main wall at the central portion thereof, said U-shape member having an upper flange affording a shield and having a lower flange equipped with a down-turned locking lug, an inner casing section comprising a main vertical wall, a bottom flange, side flanges and a top flange, the top flange being provided with a coin-slot, slot-guards mounted on the inner side of

said last-mentioned top flange, a spring-arm mounted centrally in the lower portion of the inner casing section and extending upwardly and affording a dividing wall, said 15 spring-arm being provided at its upper end with a laterally projecting locking lug and with a key-engaging lug, said main wall of said inner casing-section having a key-receiving perforation therein.

CHARLES FISHER.
